UNITED STATES PATENT OFFICE.

FRIEDRICK SCHNEIDER, OF NEW YORK, N. Y.

ROTARY VALVE.

SPECIFICATION forming part of Letters Patent No. 449,181, dated March 31, 1891.

Application filed July 5, 1890. Serial No. 357,720. (No model.)

To all whom it may concern:

Be it known that I, FRIEDRICK SCHNEIDER, of the city, county, and State of New York, have invented a new and useful Improvement 5 in Rotary Valves for Anhydrous and other High-Pressure Gases Especially for Use in Ice-Machines; and I do hereby declare that the following is a full and exact description thereof, reference being had to the accompanying drawings, and to the letters of reference marked thereon, making a part of this specification.

My invention relates to rotary reducing valves for the control of gases under pressure, 15 and more particularly to the valves in refrigerating and ice machines.

In the use of the customary valves for reducing pressure in the delivery of anhydrous ammonia and other similar gases difficulty 20 and annoyance are occasioned from the clogging of the valve by reason of the presence of solid particles in the gas, which deposit themselves in the valve-opening.

The object of my invention is to provide a 25 simple and efficient reducing-valve for the delivery of gases under pressure, which will admit of being automatically cleared by a simple reversal thereof without removal from its seat; and it consists in a novel construction 30 and arrangement of the perforated plates or disks in the valve, in combination with a clearing-pin, substantially as is hereinafter described and claimed.

In the accompanying drawings, Figure 1 is 35 a central diametric section of my improved rotary reducing-valve for the gas-pipes in ice-machines, showing the same open for the delivery of a supply of gas. Fig. 2 is a similar view of the same valve, illustrating it when 40 reversed to obtain its automatic clearance; and Fig. 3 illustrates a modification in the construction of the valve.

Similar letters indicate like parts in all of the figures.

45 A represents the body of the valve of customary form, and B the supply or high-pressure pipe, and C the delivery or low-pressure pipe connected thereto.

D is the plug of the valve transversely perforated to form a cylindrical valve-opening for the passage of the gas through it, and this transverse cylindrical opening is formed with

two shoulders or offsets e and f therein, which successively reduce its diameter.

A plate or disk G is fitted within the central portion of the cylindrical valve-opening to play freely yet closely therein against the shoulder f. This inner movable disk G is of such width as to have full bearing within the valve-opening, and its play is confined to 55 the space between the shoulders e and f by means of an outer plate or disk H, fitted to enter and close the larger end of the valve-opening and to seat itself against the shoulder e, as shown in the drawings, said outer 60 disk being secured and made fast by means of screws i i or in other suitable manner. This outer fixed disk or diaphragm H is per-

forated with one or more openings m m for the free admission of gas under pressure into 65 and through the valve, the pressure of the gas being, however, controlled and reduced in its delivery by means of a single central opening n, provided for its eduction in the movable disk G. This eduction-port n is prefer-

ably outwardly enlarged, as shown in the drawings, to facilitate its clearance. A clearing-pin R is fitted to project inwardly axially 70 from the center of the outer fixed disk or dia-

phragm H, and is made of a diameter to pass 75 readily through the central eduction-port in the movable disk G, with which it is made to

register exactly, so that when the disk G is moved inwardly toward the disk H the pin will enter said port, as shown in Fig. 2 of the 85 drawings.

In the normal operation of the valve the gas admitted under high pressure from the pipe B will enter freely through the apertures m m in the outer disk H into the central space within the valve, and its delivery 90 thence will be controlled and determined by the size of the single small aperture or eduction-port n in the movable disk G, which under the pressure will be kept closely seated 95 against the offset f and away from the clearing-pin R. The gas will thus be delivered as is customary with greatly diminished pressure into the pipe C. If, however, the eduction-port n in the disk G becomes clogged 100 and choked, so as to impede the delivery of the gas, it is only necessary to give the valve-

plug a full half-turn, and thereby bring the disk G toward the high-pressure pipe B. The

effect of this will be to drive the disk G inward toward the disk H, and this movement will cause the clearing-pin R to enter and project through the eduction-port *n*, and thereby effectually clean and clear it from any obstruction, while at the same time it will close it, and thereby close the valve against a flow of gas through it so long as it remains in this position. Upon reversing the 10 valve it will resume its customary functions with its eduction-port *n* fully cleared.

To avoid a too sharp and sudden movement of the disk G toward and against the offset *f* when the valve is reversed by suddenly bringing the high pressure of gas in the pipe B to bear upon it while it is still against the disk H, I prefer to insert a spring S between the disks G and H, so that it shall be compressed when the disk G is carried toward the disk H and operate automatically to carry it back against the shoulder *f* before, in the reversal of the valve, the high pressure is admitted through the disk H.

As a modification in the construction of the 25 valve, the outer disk H may be divided circumferentially into two sections, one of which is recessed to form an intermediate chamber *t*, as shown in Fig. 3. The perforations in the inner division U are in such case reduced in 30 number or made smaller than those in the outer section, so that the pressure of gas will be measurably reduced in passing through the two sections into the central space in the valve. Both sections are fixed so as to form 35 in effect a single piece with a central chamber *t* therein, and the clearing-pin R for the movable disk G is made to project from the inner section U in like manner as from the disk H, previously described, and to operate 40 in the same manner.

It is evident that the pin may be made to project from the movable disk into an opening pierced in the stationary disk, instead of vice versa, as above described.

45 I claim as my invention—

1. The combination, in a rotary valve, with its rotatable plug and the transverse opening therein, of a movable perforated disk mounted

to play axially in said opening, and a clearing-pin fixed to project opposite thereto to 5c register with the perforation in the disk and enter and project through the same when by a reversal of the valve-plug the disk is driven toward it and to be withdrawn therefrom when the disk is carried in the opposite direction 55 in the regular action of the valve, substantially in the manner and for the purpose herein set forth.

2. The combination, with the plug in a rotary valve, of a movable disk playing axially 60 in the transverse opening through the plug, a stationary disk closing one end of said opening, one or more supply-apertures in one of said disks, a delivery-aperture of reduced area in the opposite disk, and a pin projecting from 65 the first disk in position to enter and project through the reduced aperture in the second disk when by a reversal of the valve the one disk is driven toward the other and to be withdrawn therefrom in the ordinary action of the 70 valve, substantially in the manner and for the purpose herein set forth.

3. The combination, with the rotatable plug in a rotary valve and the opening through said plug, of a transverse disk or diaphragm 75 fixed at one end of said opening and having one or more apertures through it, a pin projecting centrally inwardly from said diaphragm, a movable disk fitted to play in said opening in front of said diaphragm and having a central perforation therein of less area than the area of the apertures through the fixed diaphragm in position to be entered and closed by the pin when the disk is carried toward the diaphragm, and a spring interposed 80 between the movable disk and diaphragm to hold them normally apart, substantially in the manner and for the purpose herein set forth.

In testimony whereof I have signed my name to this specification in the presence of 90 two subscribing witnesses.

FRIEDRICK SCHNEIDER.
